Primary Examiner — Joseph Kukella*Assistant Examiner* — Lavon M. Amerson(74) *Attorney, Agent, or Firm* — Wood Herron & Evans LLP(57) **CLAIM**

The ornamental design for a surface pattern for textile, as shown and described.

DESCRIPTION

The FIGURE is a front view of a portion of a surface pattern for textile according to the present invention. The outer broken line identifies an unclaimed boundary of the portion and forms no part of the claimed design, but is instead included to show environmental aspects thereof.

1 Claim, 1 Drawing Sheet(56)
